TOY SHOE HEEL

Ralph S. Ecoff, Chestnut Hill, Pa., assignor to Roosevelt I. Polite, doing business as Dexter Wayne Company, Lansdale, Pa.

Application May 1, 1953, Serial No. 24,782

Term of patent 14 years

(Cl. D7—5)

Fig. 1.

Fig. 2.

Fig. 3.

Fig. 4.

Fig. 5.

Fig. 6.

To all whom it may concern:

Be it known that I, Ralph S. Ecoff, a citizen of the United States of America, residing at Chestnut Hill, county of Philadelphia, and the State of Pennsylvania, have invented a new, original, and ornamental Design for a Toy Shoe Heel, of which the following is a specification, reference being had to the accompanying drawing, forming a part thereof.

I claim:

The ornamental design for a toy shoe heel, substantially as shown.
